Primary Examiner — Rosemary K Tarcza*Assistant Examiner* — Yolanda Robinson(74) Attorney, Agent, or Firm — Dean W. Russell; Renae Bailey Wainwright; Kilpatrick Townsend Stockton LLP(57) CLAIM

The ornamental design for a blade for pool cleaner, as shown and described.

DESCRIPTION

FIG. 1 is a perspective view of a blade for pool cleaner.

FIG. 2 is a front view of the blade for pool cleaner of FIG. 1.

FIG. 3 is a rear view of the blade for pool cleaner of FIG. 1.

FIG. 4 is a right side view of the blade for pool cleaner of FIG. 1.

FIG. 5 is a left side view of the blade for pool cleaner of FIG. 1.

FIG. 6 is a top view of the blade for pool cleaner of FIG. 1; and,

FIG. 7 is a bottom view of the blade for pool cleaner of FIG. 1.

The broken lines shown in the figures are for the purpose of illustrating unclaimed portions of the blade for pool cleaner, and form no part of the claimed design.
